UNITED STATES PATENT OFFICE

149,572

DESIGN FOR A LAMP

Frank Leming, San Francisco, Calif.

Application April 23, 1947, Serial No. 138,564

Term of patent 7 years

(Cl. D48—20)

To all whom it may concern:

Be it known that I, Frank Leming, a citizen of the United States, residing at San Francisco, in the county of San Francisco and State of California, have invented a new, original, and ornamental Design for a Lamp, of which the following is a specification, reference being had to the accompanying drawing, forming part thereof.

The figure is a front elevational view of a lamp showing my new design. The rear and side elevational views are substantially the same in appearance as the view shown.

I claim:

The ornamental design for a lamp, as shown and described.

FRANK LEMING.
